The ornamental design for a seat partition for a vehicle, as shown and described.

DESCRIPTION

FIG. 1 is a left perspective view of a seat partition for a vehicle showing our new design.

FIG. 2 is a left side view thereof.

FIG. 3 is a front elevational view thereof.

FIG. 4 is a rear view thereof.

FIG. 5 is a right side view thereof; and,

FIG. 6 is a right perspective view thereof in an open position.

The broken lines in the drawings depict environmental subject matter only and form no part of the claimed design.
